MINE DOOR

Tom Pat Topping, Ragland, W. Va.

Application July 9, 1943, Serial No. 494,111

2 Claims. (Cl. 246—127)

The present invention relates to new and useful improvements in sliding mine doors, and has for its primary object to provide, in a manner as hereinafter set forth, novel means controlled by an approaching train of cars for automatically and with certainty opening the doors by gravity.

Another very important object of the invention is to provide an apparatus including unique means for automatically closing the doors after the cars have passed the latter.

Other objects of the invention are to provide a slidable mine door operating mechanism which will be comparatively simple in construction, strong, durable, highly efficient and reliable in operation, and which may be manufactured and installed at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a view in side elevation of an apparatus constructed in accordance with the present invention, showing the mine track in cross section.

Figure 2 is a fragmentary view principally in elevation, looking at the opposite side of a portion of the invention.

Figure 3 is a view in horizontal section, taken substantially on the line 3—3 of Figure 1.

Figure 4 is a top plan view, showing the track mounted mechanism.

Figure 5 is a view in vertical section, taken substantially on the line 5—5 of Figure 4.

Figure 6 is a cross-sectional view, taken substantially on the line 6—6 of Figure 5.

Figure 7 is a detail view in vertical section, taken substantially on the line 7—7 of Figure 2.

Referring now to the drawings in detail, it will be seen that the embodiment of the apparatus which has been illustrated comprises a frame structure which is designated generally by reference character 1. The frame structure 1 includes upstanding end portions 2 which are erected on opposite sides of a mine track, as at 3, said end portions 2 being connected by a member 4 which bridges the track. Doors 5 are slidably mounted in the frame structure 1 and extend transversely across the track 3 when in closed position.

Rotatably mounted on a base 6 at one end of the frame structure 1 is an elongated pulley or drum 7. Mounted on the lower portion of the frame structure 1 at the other end thereof is a

10 pulley 8. An endless cable or belt 9 is trained over the pulleys 7 and 8, said belt passing beneath the rails 10 of the track 3. Depending arms 12 connect one of the doors 5 to the upper flight of the belt 9 and the other of said doors to the lower flight of said belt. In the embodiment shown, the arms 12 travel in longitudinal slots 13 which are provided therefor in the substantially channel-shaped bars 14 of the frame structure 1, in which bars the doors 5 are slidable.

Pulleys 15 are mounted on the upper portion of the frame structure 1 at the ends thereof. A cable 16 is trained over the pulleys 15 and has one end secured to the elongated pulley or drum 7 for winding thereon. Suspended from the other end of the cable 16 is a weight 17.

The shaft 18 of the elongated pulley 7 has fixed on one end portion a ratchet wheel 19. Journaled on the base 6 is a rockable shaft 20 which parallels the pulley 7. Fixed on one end portion of the shaft 20 is a pawl 21 which is engageable with the ratchet wheel 19 for releasably securing the pulley 7 against actuation by the weight 17. Fixed on the other end portion 25 of the shaft 20 is a lever 22. Another lever 23 is loosely mounted on the shaft 20. A coil spring 24 (see Fig. 2) yieldingly engages the pawl 21 with the ratchet wheel 19.

Also mounted on the base 6 is a suitable electric motor 25. A belt and pulley drive 26 operatively connects the electric motor 25 to the elongated pulley 7. A control switch 27 is provided for the electric motor 25. A cable or the like 28 connects the switch 27 to the lever 23 for closing thereby for energizing the electric motor 25. A cable or the like 29 connects the switch 27 to the adjacent door 5 for opening thereby when said door reaches its closed position for automatically stopping the electric motor 25. A feed wire a 40 extends to one terminal of motor 25, and another feed wire b extends to a fixed contact c of switch 27, while a wire d connects the movable contact e of switch 27 with the other terminal of motor 25.

45 Longitudinally aligned, rockable shafts 30 and 31 are journaled on the ties 32 of the track 3 adjacent to and parallel with one of the rails 10 of said track. The shafts 30 and 31 are installed on opposite sides of the doors 5. Wheel 50 depressed trip rails 33 and 34 are slidably mounted on the inner sides of one of the rails 10. In the embodiment shown, and as illustrated to advantage in Figure 6 of the drawings, the trip rails 33 and 34 are fixed on the upper ends of vertical rods 35 which are slidable in guides 36

which are provided therefor on the inner side of the adjacent rail 10. The rods 35 are connected, at their lower ends, by pin and slot connections 37 to arms 38 which are fixed on the rockable shafts 30 and 31.

Depending from the adjacent or inner end portions of the rockable shafts 30 and 31 are arms 39. A rod 40 connects the arm 39 on the shaft 30 to the lever 22 for actuating the shaft 20. A rod 41 connects the arm 39 which is on the shaft 31 to the lever 23 for closing the motor control switch 27.

It is thought that the operation of the apparatus will be readily apparent from a consideration of the foregoing. Briefly, with the doors 5 in closed position across the track 3, the cable 16 is wound on the pulley 7 and the weight 17 is in elevated position, as seen in Figure 1 of the drawings. The wheels of a train of cars approaching the doors engage and depress the trip rail 33 for rocking the shaft 30 in a direction to disengage the pawl 21 from the ratchet wheel 19. Thus, the pulley 7 is released and the cable 16 is unwound therefrom by the weight 17. In this manner the endless belt 9 is actuated in a direction to slide the doors 5 apart to open position in the end portions 2 of the frame structure 1. Soon after the last car of the train has passed the doors, the trip rail 34 is depressed by the wheels of the first car of the train for rocking the shaft 31. In this manner the switch 27 is closed through the elements 41, 23, 28, et cetera, for energizing the electric motor 25. The motor 25 actuates the pulley 7 in the opposite direction for closing the doors and for rewinding the cable 16 and elevating the weight 17. When the doors 5 approach their closed position, the switch 27 is opened by the cable 29 for stopping the electric motor 25.

It is believed that the many advantages of a mine door constructed in accordance with the present invention will be readily understood, and although a preferred embodiment of the apparatus is as illustrated and described, it is to be understood that changes in the details of construction and in the combination and arrangement of parts may be resorted to which will fall within the scope of the invention as claimed.

What is claimed is:

1. A mine track door apparatus comprising a frame structure mounted transversely across a mine car track, doors slidably mounted in the frame structure and adapted to extend across the track when in closed position, pulleys journaled at opposite sides of the track, an endless cable passing around said pulleys and connected to the bottoms of the doors for actuating said doors toward and away from each other respectively to closed or open positions, a weighted cable connected to one of the pulleys for operating the endless cable for moving the doors to one of said positions, releasable means to normally prevent operation of said pulley by said weighted cable, wheel-operated means on the track at one side of the doors for releasing said releasable means, an electric motor operatively connected to said pulley for operating the endless cable for moving the doors to the other of said positions, a switch 15 for controlling the motor, wheel-operated means at the other side of the doors for closing the switch, and means connecting the switch to one of the doors for opening said switch when said door reaches said other position.
2. A mine track door apparatus comprising a frame structure mounted transversely across a mine car track, doors slidably mounted in the frame structure and adapted to extend across the track when in closed position, pulleys journaled 20 at opposite sides of the track, an endless cable passing around said pulleys and connected to the bottoms of the doors for actuating said doors toward and away from each other respectively to closed or open positions, a weighted cable connected to one of the pulleys, for operating the endless cable for opening the doors, releasable means to normally prevent operation of said pulley by said weighted cable, wheel-operated means on the track at one side of the doors for releasing 25 said releasable means, an electric motor operatively connected to said pulley for operating the endless belt for closing the doors, a switch for controlling the motor, wheel-operated means at the other side of the doors for closing the switch, and means connecting the switch to one of the doors for opening said switch when said door reaches a closed position.

TOM PAT TOPPING.
